(57) CLAIM

The ornamental design for a jewelry packing box, as shown and described.

DESCRIPTION

FIG. 1 is a front right perspective view of a jewelry packing box, showing my new design;

FIG. 2 is a right side view thereof;

FIG. 3 is a left side view thereof;

FIG. 4 is a front view thereof;

FIG. 5 is a top view thereof;

FIG. 6 is a bottom view thereof;

FIG. 7 is a rear view thereof;

FIG. 8 is a front left exploded perspective view thereof, where the outer shell is slightly moved.

FIG. 9 is a front left perspective view of a jewelry packing box, where the box is open;

FIG. 10 is a right side view of a jewelry packing box, where the box is open;

FIG. 11 is a top view of a jewelry packing box, where the box is open;

FIG. 12 is a front left exploded perspective view of an open jewelry packing box, where the insert has been removed; and,

FIG. 13 is a right side exploded view thereof.

The broken lines in the drawings depict portions of the jewelry packaging box that form no part of the claimed design.

1 Claim, 13 Drawing Sheets
